ARTICLE RACK

John Chanik, Windsor, Ontario, Canada

Refiled for abandoned application Serial No.
2,810, January 21, 1935. This application
November 27, 1935, Serial No. 51,973

1 Claim. (Cl. 24—244)

This invention relates to racks and more particularly to racks particularly adapted for holding photographic films.

More particularly the invention has reference 5 to racks of the type embodying a movable pressure or rolling weight element that is easily displaceable by the introduction of a sheet into a kerf with which the rack is provided for receiving the sheet, and the return movement of said weight effects a gripping hold on the sheet to effectively resist a downward movement of the sheet.

The present application is filed in the place and stead of my application filed January 21, 15 1935, Serial No. 2,810.

The present invention together with its objects and advantages will be best understood from a study of the following description taken in connection with the accompanying drawings 20 wherein:

Figure 1 is a side elevational view of the rack.
Figure 2 is a bottom plan view of the rack.

Figure 3 is a longitudinal sectional view through the rack.

Figure 4 is a detail view taken substantially on the line 4—4 of Figure 3.

Figure 5 is a fragmentary detail sectional view with the rolling weights or balls removed and

Figure 6 is a view taken substantially on the line 6—6 of Figure 1.

Referring to the drawings by reference numerals it will be seen that the rack comprises a body 7 in the form of a substantially solid elongated bar of rectangular cross section.

Secured to the top edge of the body bar 7 is a suspension or attachment plate 9 of suitable material, the latter being secured to the bar 7 through the medium of screws 8.

The bar 7 is provided with a plurality of bores 10 or pockets of circular cross section, and inclined from the vertical.

The bores 10 open through the top of the body block 7 as at 11 and at said ends 11 are closed through the medium of the plate 9 which also serves to retain rolling weights or balls 16 within the pockets or bores 10.

At their lower ends the bores or pockets 10 are contracted as at 13 and open through the bottom edge of the body bar 7. Thus adjacent the lower ends thereof the bores 10 are provided with shoulders 12 that serve to limit the downward movement of the balls within the pockets.

Also for each bore or pocket 10 the body bar 7 is provided with a kerf or slot 14 slightly inclined from a line at right angles to the longitudinal edges of the body bar 7 in the opposite direction to the bore or pocket 10, Figure 3, and

also extending throughout the thickness of the bar to open at opposite sides of said bar. The said relative arrangement of the bores 10 and kerfs 14 enables the balls 16 to better hold a thin article such as a film.

As clearly shown in Figure 3, the kerfs or slots 14 open at their lower ends into the lower contracted end portions of the bores, and from said lower end portions the kerfs or slots extend upwardly or toward the upper edge of the body 10 bar 7 at acute angles to the bores 10.

In actual practice the rack is secured to a ceiling, or other similar support through the medium of any suitable securing devices engaging the plate 9 of the rack.

For inserting a sheet, for example a sheet 15 of photographic film into one of the slots 14 for securing the sheet to the rack, it will be apparent that as an edge of the sheet 15 is inserted into the slot 14 through the lower end thereof 20 said sheet will contact the ball 16 raising the same upwardly a distance sufficient to permit insertion of the sheet 15 into the slot 14 a required distance. When the sheet has attained the required height in the slot 14 the hand may 25 be released therefrom permitting the sheet to drop down by gravity when the pressure of the ball against the face of the sheet will act to effectively clamp the latter against the remote side wall of the slot 14 in such a manner that 30 the sheet will remain suspended.

To remove the sheet from the rack the sheet is first moved upwardly in the direction of the arrow A to loosen the grip of the ball on the sheet, then the sheet is pulled in a lateral direction, or in the direction indicated by the arrow B all of which will be clear from a consideration of Figure 4.

Having thus described the invention, what is claimed as new is:

The herein described rack consisting essentially of a ball, and a bar having therein a bore of circular cross section in which the ball is disposed, and also having a kerf extending throughout the thickness of the bar and fully open at 45 opposite sides thereof; the bore being inclined from the vertical and having a lower contracted end open at the underside of the bar and forming in the bore a shoulder to limit downward movement of the ball, and the kerf being 50 straight and open at its lower end to the lower contracted end portion of the bore, and also being extended upwardly from said portion and inclined from the vertical in a direction opposite to the inclination of the bore.

JOHN CHANIK.
